(57) **CLAIM**

The ornamental design for a firearm handguard mount tension block, as shown and described.

DESCRIPTION

FIG. 1 is a perspective view of a firearm handguard mount tension block incorporating my new design viewed from behind, above, and a left side thereof;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a bottom plan view thereof; and,

FIG. 7 is a top plan view thereof.

The uniformly broken lines shown in the figures represent portions of the firearm handguard mount tension block that form no part of the claimed design. The dot-dashed broken lines shown immediately adjacent the shaded areas represent boundaries to the claimed design and forms no part of the claimed design. The unshaded areas between broken line structures form no part of the claimed design.

1 Claim, 7 Drawing Sheets
